(57) **CLAIM**

The ornamental design for an optical reflex sight, as shown and described.

DESCRIPTION

FIG. 1 is a top front right isometric view of a design for an optical reflex sight according to a first embodiment;

FIG. 2 is a top rear left isometric view thereof;

FIG. 3 is a bottom front left isometric view thereof;

FIG. 4 is a front view thereof;

FIG. 5 is a rear view thereof;

FIG. 6 is a left view thereof;

FIG. 7 is a right view thereof;

FIG. 8 is a top view thereof; and,

FIG. 9 is a bottom view thereof.

The broken lines in the drawings disclose unclaimed portions of the optical reflex sight only and form no part of the claimed design.
